MANUALLY OPERATED IRRIGATOR

Filed July 20, 1927

UNITED STATES PATENT OFFICE

BERTHA SJÖSTRÖM, OF LOS ANGELES, CALIFORNIA

MANUALLY-OPERATED IRRIGATOR

Application filed July 20, 1927. Serial No. 207,076.

My invention is a manually operated irrigator adapted for attachment to a hose or the like, and is adapted to give a wide and a narrow water spray.

5 An object of my invention is a water irrigator having a casing adapted for connection to a pipe to which a hose may be attached. The casing has a row of perforations in alignment for discharging water, and the supporting metal at these perforations forming the nozzle jets is given a bend, positioning the nozzle jets at an angle to the plane of the end of the casing. The back of the casing from the forward end, through which the jets extend, is tapered rearwardly and inwardly. 10 The top and bottom sides diverge slightly from the face having the nozzle or jet opening.

15 A further object of my invention is the construction of a water irrigator in which certain of the perforations at each side of the center perforation are inclined inwardly towards the center to such an extent that the streams of water diverging in the irrigator from the attachment to the handle are diverted to form parallel jets of water in alignment with the center stream from the center jet.

20 My invention is illustrated in the accompanying drawings, in which:

25 Figure 1 is a perspective view of my irrigator showing the manner of use.

Figure 2 is a face elevation taken in the direction of the arrow 2 of Fig. 1.

30 Figure 3 is a horizontal section on the line 3—3 of Fig. 2 in the direction of the arrows.

Figure 4 is a side elevation taken in the direction of the arrow 4 of Fig. 3.

35 The irrigator comprises a casing 11 which has upper and lower walls 12, a front face 13, two end walls 14 and rearwardly and inwardly converging rear walls 15. Viewed from the face in a horizontal view, as shown in Fig. 2, it will be noted that the ends 16 have the top and bottom walls substantially parallel and at the center 17 there is a swelling or spreading apart of the top and bottom walls. In other words, these walls diverge from the face 13, and these top and bottom walls and the rear walls 15 are at-

tached to the coupling 18 which has a screw-threaded socket 19. A handle pipe 20 may be secured in this socket and a hose 21 secured to the handle.

40 The face of the casing has a series of perforations 22 adjacent the end which are punched or cut through a portion 23 of the front wall which is flat. The next series of nozzle jet perforations 24 have the wall kinked or bent as indicated at 25, so that the center line of these nozzles is inclined inwardly, as indicated by the line 26; whereas the axial center of the nozzle jets 22 is at right angles to the face 13, as indicated by the center line 27. The center perforation 45 28 is in a flat section 29 of the front face and its axial line 30 is at right angles to the front face 13.

45 In constructing the casing in forming the irrigator it is not necessary that the front 50 face have right angular corners joining the top and bottom walls 12, as these may be merged with a round curve. I find a convenient way to manufacture the irrigator with the nozzle jets inclined at an angle is to 55 have these apertures perforated with their axial lines at right angles to the front face 13 and then with a round implement inserted through the nozzle, to bend the adjacent metal, inclining the axis of each nozzle 60 inwardly on opposite sides of the center.

55 The manner of operation and functioning of my irrigator as thus constructed is substantially as follows:

65 On account of the water having a freer flow directly from the pipe 20 at the center of the casing in the ordinary construction with the jet nozzles all at right angles to the front face, a greater flow of water would pass through the center than at the sides, 70 and thus the spray would not be even. However, with my construction, the water jets are even from one end to the other of the front face and thus give an even spread of the water, with substantially as much water 75 flowing through the nozzle jets 22 adjacent the opposite ends of the casing as through the center nozzle jet 30, or the inclined jets 24. Therefore, in watering plants, or irrigating, when the irrigator casing is moved 80

over the strip of plants or garden to be covered with water, having the face 13 at right angles to the direction of motion, an even flow of water is spread from one end to the other of the front face 13.

5 In the action of my irrigator the water under relatively high pressure passing through the tubular handle 20 at the center has a straight flow through the center jet 10 and causes a stream 30 in alignment with the handle. The jet openings at each side of the center have their axes pointing towards the axis of this center jet so that as the water in the casing 11 having a direction of flow 15 towards the ends 14 is diverted to such an extent that the jet of water from each of the inclined orifices is parallel to the center stream 30. The water that passes out of the jet orifices adjacent the ends 14 has been 20 given a slight turn in direction by the inclined back 15 so that these jet orifices may have their axes parallel to the center jet and give a series of parallel streams of water. The inclination of the axes of the openings is 25 to deflect water which flows in a forward and an outward direction to a direction which is parallel to the axis of the center jet 30.

Various changes may be made in the principles of my invention without departing 30 from the spirit thereof, as set forth in the description, drawings and claims.

I claim:

1. An irrigator comprising a casing having a narrow face, and top and bottom walls 35 extending rearwardly therefrom and rear walls converging inwardly from the face, the rear walls and top and bottom walls terminating in a coupling, the front wall having a straight row of perforations from 40 end to end, the center perforation and some of those adjacent the ends having their axes at right angles to the face and the other perforations having their axes inclined on the outside of the front wall inwardly towards the center.

2. An irrigator comprising a casing having a face wall of sheet metal in substantially one plane with a series of perforations in a straight row from end to end of said 50 wall, the wall being bent between some of the perforations so that the axes of such perforations adjacent the bent portion of the wall are inclined on the outside of the front wall to the plane of the face wall.

55 3. An irrigator comprising a casing having a front face wall formed of sheet metal with a series of perforations therethrough from end to end in a straight row, some of the perforations adjacent the outside edge 60 having their axes at right angles to the face and some of the other perforations having the metal between same bent whereby the axes of such latter perforations are inclined on the outside of the front wall towards the 65 center of the front face wall.

4. An irrigator having a casing with the front face with perforations and an inlet at the back in substantially the center, the center perforation having its axis in alinement with the intake, some of the perforations on each side having their axes inclined on the outside of the front wall inwardly toward the center perforation and some of the perforations at the extreme outside having their axes parallel to the center perforation whereby the outwardly flowing water in the irrigator is diverted by the inclined perforations to give parallel streams at each side of the center parallel to the center stream, and the back of the casing converging from the ends to the center whereby the streams from the extreme outside perforations are parallel to the center stream.

5. An irrigator comprising a casing having a front wall with a straight row of perforations, an intake to said casing in the back thereof, a perforation in alinement with the intake having its axis normal to the center portion of the front wall, sections of the front wall having bends with perforations between said bends, the rims of said latter perforations having one portion outside and the other slightly inside of the plane of the center portion of the said front wall, whereby said latter perforations have their axes inclined inwardly on the outside of the front wall in reference to the center perforation.

6. An irrigator comprising a casing having a front wall formed of sheet material with a straight row of perforations, there being an intake through the back casing, the center perforation being in alinement with the intake and having its axis normal to the front wall, a plurality of additional perforations on opposite sides of the center perforation being formed between kinks or bends in the front wall, whereby the plane of each of said additional perforations formed through its edges is inclined to the front wall and the axis of each of the additional perforations is inclined on the outside of the front wall inwardly towards the axis of the center perforation.

7. An irrigator comprising a casing having a narrow front wall, rear walls converging from the front walls towards a central intake, the front wall having a straight row of perforations, the center perforation being in alinement with the intake and having its axis normal to the plane of the front wall, there being a plurality of additional perforations on each side of the center perforation formed between kinks or bends of the front wall, whereby the plane of each of said additional perforations formed by the rim of said perforations is inclined to the front wall, whereby the axes of such additional perforations are inclined on the outside of the front wall inwardly towards the axis of the center perforation.

8. An irrigator comprising in combination
a casing having a narrow front wall, rear
walls converging from the ends of the front
wall to a central intake, top and bottom
walls extending from the front wall to the
said intake and to the rear walls, there being
5 a row of perforations in the front wall, the
central perforation having its axis in alignment
with the intake, the additional perforations
on opposite sides of the center perforation
10 having their axes inclined on the outside
of the front wall inwardly towards
the axes of the center perforation.

15 In testimony whereof I have signed my
name to this specification.

BERTHA SJÖSTRÖM.
